(57) **CLAIM**

The ornamental design for a cutting tooth holder and tooth, as shown and described.

DESCRIPTION

FIG. 1 is a front, top right side perspective view of a cutting tooth holder and tooth embodying my design;

FIG. 2 is a rear elevational view of the cutting tooth holder and tooth as shown in FIG. 1;

FIG. 3 is a front elevational view thereof;

FIG. 4 is a top plan view thereof;

FIG. 5 is a bottom plan view thereof; and,

FIG. 6 is a left side elevational view thereof.
